ABSORPTION REFRIGERATION SYSTEM

Nelson T. Branche, Shaker Heights, Eric H. Ryden, East Cleveland, and Albert C. Schickler, Beechwood, Ohio, assignors to The Bryant Heater Company, Cleveland, Ohio, a corporation of Ohio

Application November 26, 1937, Serial No. 176,518

14 Claims. (Cl. 62—120.5)

This invention relates to refrigeration systems of the type having an evaporator and means for periodically serving the same with volatile refrigerant, latent heat of evaporation of which serves in transfer of heat from what is to be cooled.

An object of the invention is to provide novel means for automatically draining from the evaporator, at each cycle of operation of the system, a small amount of liquid, including such relatively non-volatile substances as might otherwise accumulate in and impair the efficiency of the evaporator.

The invention is particularly adaptable for the usual absorption refrigeration system wherein the evaporator is served, through suitable connections, by a generator-absorber arranged to operate in alternate heating and cooling stages ammonia and water for example being employed as refrigerant and absorbent respectively, the delivery connection from the generator-absorber to the evaporator including means designed to prevent absorbent from finding its way to the evaporator while providing delivery of refrigerant thereto in liquid form; such a system being old and well known in the art.

The absorbent being heavier than the refrigerant, the invention contemplates drainage from a lower part of the evaporator, so that should any absorbent find its way to the evaporator it will be removed; and the invention contemplates return of the drained liquid to the generator.

The invention employs siphon means for the drainage function, with associated receiver, restriction and vent means, so related with each other and with the evaporator that, as important objects of the invention, drainage commences responsive to liquid level within the evaporator and terminates after a predetermined relatively small quantity of the liquid has been removed.

A still more important object, with respect to the generator-absorber, is to provide that the drainage takes place generally at the end of the heating stage and just before start of the cooling stage, so that refrigerant included in the drainage liquid will serve to accelerate the initial absorbing action. More particularly the generator-absorber is preferably provided with an absorption loop into which the drained liquid is introduced to set up circulation by its heat of absorption.

The exact nature of the invention together with further objects and advantages thereof will be apparent from the following description taken

in connection with the accompanying drawings, in which Fig. 1 is a conventionalized diagrammatic view showing an absorption type refrigeration system in which an embodiment of the invention is incorporated; Fig. 2 is a similar view of the evaporator part of such system with a modified form of the invention applied thereto; and Figs. 3 and 4 are end and side elevations of evaporator and associated parts illustrating the invention in another modified form.

With reference now to the drawings and first to Fig. 1 thereof, G is a generator-absorber and E an evaporator, these being the principal units of the system.

The generator has an associated heater H and an absorbing loop g. There is a delivery connection L₁ from the top of the generator to the top of the evaporator by way of a trap T, a rectifier R and a condenser C.

The evaporator E comprises a storage tank E' and therebelow the usual heat exchanging or cooling coil e which, it will be understood, extends within the chamber to be cooled. A return line L₂ leads from the upper part of the evaporator to the sloping "up" leg of the absorbing loop g of the generator-absorber.

The system is sealed closed and contains a volatile refrigerant and an absorbent therefor, such as ammonia and water respectively, in suitable proportion and volume.

What has thus far been described is old and well-known in the art, and its general operation is cyclic, in two stages, as follows:

Commencing with the absorbed refrigerant in strong solution in the generator-absorber, and the evaporator E substantially empty, heating of the generator by operation of the heater H drives off the refrigerant as a gas. The refrigerant under pressure finds its way to the evaporator E through the trap T and rectifier R which generally prevent passage of absorbent, and the condenser C wherein the refrigerant is liquefied, so that ultimately the evaporator E is largely filled with liquid refrigerant and the generator principally with absorbent only or weak solution. Operation of the heater H is then terminated by suitable control means not shown and forming no part of this invention, which completes the heating stage of the cycle.

Thereupon as the generator-absorber cools, the liquid refrigerant in the evaporator E gasifies and returns to the generator-absorber to be reabsorbed in the absorbent therein, by way of the line L₂ and the loop g of the generator-absorber, the trap T preventing return by way of

the line L_1 . During this stage circulations and evaporation of liquid refrigerant takes place in the heat-exchanging coil e , taking up heat from the surroundings of the coil. Also circulation takes place in the loop g of the generator, as indicated in the drawings. Ultimately most of the refrigerant having been evaporated in the evaporator and reabsorbed in the generator-absorber, the cooling stage, and thus the entire refrigeration cycle, has been completed.

It will be apparent that should any absorbent find its way to the evaporator, being substantially or relatively non-volatile, it will therein be trapped and accumulate at the bottom, and impair the efficiency of the system and ultimately render it inoperative.

Our invention provides automatic drainage of a small amount of liquid from the bottom of the evaporator with each cycle, at the latter part 20 of the heating stage and thus just before commencement of the cooling stage, and employs siphon means for the purpose. This siphon means as here shown, includes an "up" leg 1 and a "down" leg 2 connected to the line L_2 , preferably 25 with a reservoir chamber 3 between the legs. The up leg 1 of the siphon has connection with the evaporator by way of a receiver 4 . The receiver 4 has connection with the bottom of the down leg of the evaporator coil e , and this by way of a 30 small opening provided by a restriction 5 . The receiver 4 is vented effectively to the top of the evaporator as by a connection 6 here shown as to a high part of the line L_2 .

The siphon means and associated parts are so 35 proportioned and arranged that they operate as follows. During the heating stage liquid rises within the evaporator, the connection 6 and the up leg 1 of the siphon, maintaining substantially the same level in each, residue liquor from 40 the preceding cooling stage, including some liquid refrigerant, finding its way to the receiver 4 and thence into the connection 6 and siphon leg 1 . As the heating stage nears completion and the evaporator is nearly full, the liquid level 45 rises high enough in the siphon reservoir 3 to overflow into the down leg 2 of the siphon and thus prime the latter and initiate siphonic action. Because of the vent connection 6 , this siphonic action is greatly accelerated at the start 50 due to the high liquid in this connection so that the whole system $4, 6, 1, 2$ is rapidly evacuated even if the lower end of tube 2 is located only slightly below the hollow of the receiver 4 . Some flow takes place past the restriction 5 but greatly 55 less than that in the siphon, so that the receiver 4 and up leg 1 of the siphon, together with the vent connection 6 , are quickly emptied, the siphon broken and drainage terminated. The action is that of quickly draining a small shot of 60 rich liquid from the bottom of the evaporator.

This shot is delivered by the line L_2 to the loop g of the generator-absorber where, because the shot is of strong solution relative to the weak solution within the absorber, reabsorption 65 instantly commences, and circulation in the loop g is quickly initiated through thermosiphonic action due to heat of absorption. Thus when the cooling stage is commenced, absorption can take place immediately as the required circulation in 70 the absorption loop g already is established.

With reference now to Fig. 2, a modified form 75 of the invention is shown as applied to the evaporator, which latter will be understood as incorporated in a complete system such as that indicated in Fig. 1.

Here the receiver $4a$ is located to extend partly within the storage tank part E' of the evaporator, the vent $6a$ being short and into a dome of this tank part, and a supply connection 10 leading from the down leg of the evaporator coil e 5 up to the receiver. A restriction $5a$ is provided in this connection 10 adjacent the coil e . A bell member is arranged over the down leg $2a$ of the siphon to provide a short annular siphon supply leg $1a$.

The operation of this modification will be generally as before, the draining being accomplished by siphonage at the latter part of the heating cycle, responsive to liquid level in the evaporator part E' , drainage being of a limited quantity of 15 liquid determined by the combined volume of the receiver $4a$ and the supply leg $1a$, breaking of the siphon being determined by the level of the bottom of this leg.

The advantages of this modification are that 20 of the receiver $4a$ has protection by the evaporator part E' against heat leakage from the outside, and also gas bubbles formed in the supply connection, are allowed to vent directly upwardly into the evaporator vapor space, eliminating the danger of the siphon being primed during the absorption period due to refrigerant evaporating in this supply leg.

With reference now to the modification of Figs. 3 and 4, the arrangement is generally similar to 30 that of Fig. 2 but the receiver $4b$ is located wholly within the storage part E' of the evaporator, and its supply connection $10b$ located within the down leg part e' of the evaporator cooling coil e .

To position the lower end of the connection $10b$ a partition 11 is arranged thereabout, fitting within the surrounding cooling coil leg e' , the latter extending downwardly below the cooling coil branches indicated. To provide restricted 40 inlet to the connection $10b$ it is perforated as at $5b$ above the partition 11 . Thus a sump is formed below the opening $5b$ and particularly below the partition 11 , in which solid foreign particles will be permanently trapped.

A vent $6b$ is provided above the supply connection $10b$, a siphon supply leg $1b$, and the down leg $2b$ of the siphon leads to the line L_2 , all as before. The lower edge of the dome which provides the supply leg $1b$ is sloping as indicated, 50 to accurately and conveniently position the dome in the receiver $4b$.

In this arrangement the drain parts being surrounded by cold refrigerant liquid within the evaporator, no gasification will occur in the siphon supply leg tending to raise the level there-in above the top of the down leg of the siphon which would cause loss of refrigerant.

What we claim is:

1. In a refrigeration system having an evaporator, and refrigerant-serving means therefor including a generator-absorber arranged to operate in alternate heating and cooling stages: siphon means arranged to provide drainage from a low part of said evaporator commencing responsive to liquid level therein, and having vent means to the top of said evaporator and a cooperative restriction therebelow, for terminating said drainage.

2. In a refrigeration system having an evaporator, and refrigerant-serving means therefor including a generator-absorber arranged to operate in alternate heating and cooling stages: a receiver having restricted communication with a low part of said evaporator and vent communi- 75

rator with interconnected upper storage and lower heat exchanger parts, and refrigerant-serving means for said evaporator including a generator-absorber arranged to operate in alternate heating and cooling stages: a receiver having restricted connection with said evaporator heat exchanger part and vent connection with said evaporator storage part, and siphon means arranged to empty said receiver responsive to liquid level in said evaporator storage part, said receiver being located within said evaporator storage part and its said restricted connection being located principally within a leg of said evaporator heat exchanger part, and partition means positioning said restricted connection in said leg.

14. In a refrigeration system having an evaporator with interconnected upper storage and lower heat exchanger parts, and refrigerant-serving

means for said evaporator including a generator-absorber arranged to operate in alternate heating and cooling stages: a receiver having restricted connection with said evaporator heat exchanger part and vent connection with said evaporator storage part, and siphon means arranged to empty said receiver responsive to liquid level in said evaporator storage part, said receiver being located within said evaporator storage part and its said restricted connection being located principally within a leg of said evaporator heat exchanger part, and partition means positioning said restricted connection in said leg, said restricted connection having a lateral opening above said partition means.
